SIGNALING SYSTEM FOR SINGLE-TRACK
RAILROADS

Reed B. Annear, Omaha, Nebr., assignor to Westinghouse Air Brake Company, a corporation of Pennsylvania

Application January 25, 1949, Serial No. 72,568

5 Claims. (Cl. 246—3)

1

My invention relates to signaling systems for single track railroads, and more particularly, to single track signaling systems of the normally inactive reversible coded track circuit type such as the one shown and described in reissue patent of the United States, No. 22,780, reissued August 13, 1946, to J. J. Van Horn, for Railway Traffic Controlling Apparatus, which system is also described in an article on pages 423-431 of the August 1944 issue of the magazine Railway Signaling, published by the Simmon Boardman Publishing Corporation of Chicago, Illinois.

In signaling systems of this character, continuous track circuits are provided for all main track, and a centralized traffic control system is employed to enable the reversible track circuit system for the single track stretches between passing sidings to be set up for either direction of traffic movement and to enable the head block signals which govern movements into the single track blocks, as well as the entering signals which govern traffic movements into the passing tracks at the ends of the blocks, to be manually controlled from a central office.

A characteristic of the Van Horn system is that the track circuits for the successive sections of a block have track relays and batteries at both ends, and normally a battery is connected to the rails at the entrance end of the block, for the traffic direction established, and the track relays at the exit ends of the sections are energized in cascade, the track relay at the exit end of the last block section controlling an indicator at the office to indicate that the entire block is vacant. Under this condition the operator is enabled to reverse the traffic direction by energizing a traffic control relay at one end and releasing a similar traffic control relay at the other end of the block by remote control, thereby disconnecting the battery at the one block end and connecting a battery to the rails at the other block end whereupon the track relays at the opposite ends of the sections become energized in cascade. The system thus is normally in an inactive condition in which all of the track circuits are energized by steady current in a direction corresponding to that established for traffic movements, which direction is the opposite to that required for the control of the signals governing such movements.

To place the system in its active condition and to clear the head block signal which governs traffic movements into the block in the established direction, the operator at the control office, by remote control, energizes a signal con-

2

trol relay at the entrance end of the block, and this relay prepares a circuit for the associated signal and also disconnects the adjacent battery from the track rails. The resulting deenergization of the cascade connected track circuit system in this case has the effect of preventing a subsequent reversal in the traffic direction, and in addition, causes coded current interrupted periodically at the rate of 75 or 180 times per minute to be supplied to the rails at the exit end of the block for signal control purposes, and the track circuits then become energized in cascade by coded current, to clear the head block signal having its control relay energized. When a train governed by that signal enters the block, its signal control relay releases and automatically restores the system to the inactive condition above described.

In addition to the manually controlled head block signals referred to, the system also includes intermediate signals at spaced locations in the single track block such as those shown in Fig. 1c of the Van Horn patent, which signals are governed automatically to indicate caution or proceed in accordance with traffic conditions, when 75 or 180 coded current is received over the track rails of the block section in advance, and also govern the supply of such current to the rails of the section in the rear.

Conventionally, 75 code is supplied to the rails at the exit end of the block when the signal which governs train movements out of the single track stretch is at stop, and 180 code is supplied when that signal indicates caution or proceed.

At each intermediate signal location, 75 code is supplied to the rails of the section in the rear of the signal which governs train movements in the established direction when the advance section is occupied, and 180 code is supplied to the rails of the rear section when 75 or 180 code is received from the rails of the advance section.

My invention relates to the control of intermediate signals in a system of this character in a situation where the single track block is so short that the conventional arrangement shown in Fig. 1c of the Van Horn patent is not applicable and it is necessary to stagger the signal locations and to overlap the control limits for the intermediate signals and also those for the signals in approach thereto in order to provide adequate stopping distances for high speed trains.

More specifically, the principal object of my invention is to provide the proper control limits

for the intermediate signals and for their approach signals to enable the Van Horn system to function in its intended manner in a situation which differs from that illustrated in Fig. 1c of the Van Horn patent by the fact that it is necessary to overlap the block sections which govern the opposing signals shown in that view by removing the westbound signal $7W$ shown at location E and replacing it by one at location F , without shortening the control limits for the westbound approach signal in the rear thereof, such as signal $10LA$ in Van Horn's Fig. 1d, and by extending the control limits for the eastbound signal in the rear of signal $7E$ through point E to point F .

My invention is applicable to any stretch of railway track equipped with a coded track circuit signaling system of the type referred to, which is divided into three track sections arranged to provide two overlapping block sections having a common portion comprising the intermediate track section of the stretch, with intermediate signals at the opposite ends of the intermediate track section and approach signals at the end of the stretch each governed in accordance with traffic conditions in the block section in advance of the signal.

Heretofore in a situation of this kind it has been necessary to provide a complete set of traffic and signal control apparatus for a pair of opposing intermediate signals such as is shown in Van Horn's Fig. 1c, at each intermediate signal location even though there is only one signal at such location.

My invention enables the amount of apparatus required to be materially reduced, and as in the Van Horn patent, I provide a complete set of traffic and signal control apparatus at the location of the first intermediate signal only, and at the location of the second intermediate signal I also provide cut-section apparatus to enable the intermediate track section and the second end section to function as a single block section for the control of the first intermediate signal and of the approach signal in the rear of the second intermediate signal, at the opposite end of the same block section.

In accordance with a feature of my invention, this second intermediate signal is controlled over a line circuit governed by traffic conditions in the intermediate section and first end section, and means are provided for preventing the clearing of the approach signal in the rear of the second intermediate signal unless this line circuit is energized.

Another feature of my invention resides in the means for the control of the approach signal in the rear of the first intermediate signal. In accordance with this feature of my invention, I supply to the rails of the intermediate section, at the location of the first intermediate signal, coded current of a character to which the cut-section apparatus is nonresponsive, such as current of reverse polarity, for example, when a train governed by the first intermediate signal occupies either the intermediate track section or the second end section. I also provide an additional track relay selectively responsive to current of reverse polarity at each end of the intermediate track section. One of these track relays controls train detecting means for governing the supply of coded track circuit energy to the rails of the first end section for the control of the approach signal at its remote end, while the other track relay serves to restore the

track circuit apparatus to normal when the second end section is vacated.

I shall now describe one form of apparatus embodying my invention and shall then point out the novel features thereof in claims.

In the accompanying drawings, Figs. 1 and 2 taken together illustrate the circuits and apparatus for the control of a pair of opposing intermediate signals in a signaling system of the type shown in the Van Horn patent referred to, for use in place of that shown in Fig. 1c of the patent. More particularly, the apparatus of Fig. 1 is for use at the signal location E of Fig. 1c of the patent, and that of Fig. 2 is for use at the cut section location F . As shown, Fig. 2 shows "back contact coding cut section" apparatus, the operation of which corresponds to the alternative form provided for use at location E by Van Horn and shown in his Fig. 5.

Similar reference characters refer to similar parts in both views, and the local sources of current for energizing the various local circuits are identified in the usual manner by the reference characters B and C . Furthermore, reference characters similar to those of the Van Horn patent have been used to identify each of the relays which has a counterpart in the Van Horn patent. Van Horn's signal $7W$ has been replaced by a signal $9W$ at location F , Fig. 2, which is governed by a polar neutral relay $9HDR$ controlled over line wires 21 and 22 by the code detector relay $7HTR$ at location E . To meet the requirements of a particular railroad, Van Horn's position light signals have been replaced by color light signals and an auxiliary motor car indicator system provided for warning the operators of hand cars or the like of the approach of trains. The motor car indicators, not shown, are controlled by circuits governed by repeating relays such as the relays $1WTPR$, $1ETPR$ and $9ETPR$ which are controlled over circuits including the line wires 23 , 24 and 25 and a common return wire 26 extending the length of each block section, by the track repeating relays of the signaling system. Although the motor car indicator system forms no part of my invention, these repeating relays are shown because they are used to provide approach lighting for the signals.

Each of the track relays shown herein is of the biased polar type as indicated conventionally by an arrow on the relay winding, each such relay being responsive to current of the polarity supplied by the battery at the remote end of its section, but not to current from the adjacent track battery.

The circuits of Fig. 1 for supplying energy to the rails of section $7RT$ have been modified in accordance with my invention by including contacts of a pole changer relay $7TPC$ therein, and also the winding of a track relay $AETR$ responsive to current of the opposite polarity to that which track relay $1ETR$ is responsive. Relay $AETR$ controls a slow release repeating relay $AETP$. A similar track relay $AWTR$ and repeating relay $AWTP$ are included in the circuits of Fig. 2. Relay $7TPC$ is normally energized and is released only when an eastbound train is occupying section $E-F$.

The track circuit system as shown is in its normal inactive condition as set up for westbound traffic, with the westbound traffic control relay $8WFSR$ energized and the eastbound traffic control relay $8EFSR$ released, and with the signal control relays $6RHSR$ and $10LHSR$ released, so that relay $10LTCTM$, which it is to be under-

stood, is controlled as shown in Fig. 1d. of the Van Horn patent, is steadily energized and is supplying current from the battery 1S to the rails of section 10LT. In Fig. 2, the track relay 9ETR and its slow release repeating relay 9ETFSA are steadily energized. The transmitter relay 9WCTM is energized over front contact 196 of relay 9ETFSA, its circuit extending to terminal B at back contact 195 of a relay 9CD, and is supplying steady current to the rails of section 7RT. Relay 9CD is a code detector relay which replaces the relays ETBSA and WTBSA of Van Horn's Fig. 5.

In Fig. 1, the track relay 9ETR and its slow release repeating relay 9ETFSA are steadily energized, and the code transmitter relay 9WCTM is energized over contacts 60—63, as in the Van Horn patent, and is supplying current to the rails of section 6RT so that relays 6RTR and 6RTFSA are steadily energized.

Assuming now that the operator energizes relay 10LHSR to set the system into operation and to clear the signal for westbound traffic, relay 10LHSR will open the circuit for relay 10LTCTM and the energized relays above described will release in cascade, and relay 6RTFSA upon releasing will connect relay 6RTCTM either to terminal 180B or to terminal 75B of a suitable source of coded current, depending upon whether or not signal 6L has been cleared to cause relay 6RTCTM to supply coded current to the rails of section 6RT, as explained in the Van Horn patent.

In Fig. 1, the first impulse of coded current picks up relays 9WTR and 9WTFSA, and relay 9ECTM is energized over back contacts 69, 68 and 76 and front contact 73 to supply current to the rails of section 7RT so that in Fig. 2, relays 9WTR and 9WTFSA pick up and relay 9ECTM is energized to supply current to the rails of section 10LT so that relays 10LTR and 10LTFS pick up. At the end of the first code impulse received by relay 9WTR, a code detector relay 7CD, which replaces Van Horn's relay 7BSA, picks up over back contact 178 and front contact 179 and a back contact of relay 7ETFSA and completes a circuit for the primary winding of the decoding transformer DT. The current supplied to transformer DT is periodically reversed in polarity by the code operation of a contact of relay 9WTR in this circuit, causing alternating current of the code frequency to be induced in its secondary winding. This alternating current is rectified by contact 180 of relay 9WTR so that the signal relay 7HR becomes energized. Relay 7HR responds to either 75 or 180 code, and governs the stop and caution aspects of signal 7E. The proceed aspect of signal 7E is governed by a signal relay 7DR which is selectively energized through a resonant decoding unit 180DU when transformer DT is supplied with 180 code.

When relay 7HR picks up, the directional stick relay 7WS is energized over contacts 70, 71 and 72, and the opening of back contacts 68 and 76 in the circuit for relay 9ECTM causes it to release, so that in Fig. 2, relay 9WTR releases and picks up relay 9CD. The signal relay 9HDR in Fig. 2 now picks up over front contacts of relays 9WTFSA and 9CD, line wires 21 and 22, the pole changer contacts of relay 7DR and front contacts of relay 7HR and 7WTFSA. Relay 9HDP is connected in series with relay 9HDR in this circuit and also picks up, and by closing its front contact completes

a circuit for relay 9ECTM which extends over back contact 69, front contacts 68 and 67 to terminal B at back contact 60.

Two code transmitters 15CT and 180CT of the pendulum type, which close their contacts 75 and 180 times per minute respectively, are set into operation by the energization of relay 7WS, and the periodic operation of contact 67 causes relay 9ECTM to supply 180 code to the rails of section 7RT to operate relay 9WTR.

The continued code operation of relay 9WTR maintains relays 9WTFSA and 9CD picked up, and the periodic closing of its back contact causes relay 9ECTM to supply 180 code to relay 10LTR which code is opposite in phase to that supplied to relay 9WTR. The purpose of this "back contact coding" is to provide compensation when the on and off periods of the code are not equal, due to over-energization or under-energization of the track circuits.

The head block signal 10LA will now display a proceed indication, for reasons explained in the Van Horn patent.

It will now be assumed that a westbound train governed by signal 10LA passes through the block. When the train enters the switch section 9T, the track relay 9TR releases and picks up a directional stick relay 10LSR over a contact closed by signal 10LA in its energized position. Relay 10LSR is held energized over a stick circuit following the return of the signal to stop, until the train vacates sections 9T and 10LT and coded current is received over the rails of section 10LT. When the train enters section 10LT, and shunts the track relay 10LTR, relay 10LTFS will release, disconnecting terminal B from line wire 25 so that relay 9ETPR will release to complete the lighting circuit for signal 9W, energizing lamp G or Y to cause the signal to indicate proceed or caution, depending upon whether relay 9HDR is energized by current of normal or reverse polarity. Current of normal polarity is supplied to relay 9HDR only when sections D—E and E—F are supplied with 180 code and relay 7DR occupies its energized position.

When the westbound train referred to enters section 7RT, the track relay 9WTR is shunted, releasing relays 9WTFSA, 9CD, 9HDR and 9ECTM. Lamps G and Y of signal 9W are dark and lamp R is lighted to indicate stop, due to the release of relay 9HDR by relays 9WTFSA and 9CD. The series connected relay 9HDP also releases and shifts the circuit for relay 9ECTM from contact 67 to contact 75 so that 75 code is supplied to the rails of section 7RT in front of the train.

The purpose of this 75 code connection is to enable relays 9CD and 9HDP to be picked up, so as to cause the circuit for supplying 180 code to section 7RT to be re-established, in the event the train vacates section 7RT without occupying the advance section 6RT.

Assuming however, that the westbound train enters section 6RT, relay 9WTR will be shunted and will release relays 9WTFSA, 7CD, 7HR and 7DR. Relay 9WTFSA releases relay 7WTPR to light lamp R of signal 7E, and completes a stick circuit for relay 7WS over contacts 13 and 14 so that relay 7WS remains picked up.

When the westbound train vacates section 7RT, relay 9ECTM is set into operation over the circuit including back contacts 69 and 68, front contacts 76 and 75 and back contact 60 to supply 75 code to the rails of section 7RT,

which code is repeated by the cut section apparatus of Fig. 2 into the rails of section 10LT.

Ordinarily the signal control relay for signal 10LA is released as soon as the train passes the signal, but if relay 10LHSR is now energized, this signal will indicate caution. Otherwise the system will return to its inactive condition in the manner explained in the Van Horn patent, the reception of coded current at point G by relay 10LTR releasing relay 10LSR and causing relay 10LTCTM to become energized to supply steady current to the rails of section 10LT, in which case relay 9ETR will pick up during the periods when relay 9ECTM is released. Since these are the periods during which relay 9WTR is picked up, the circuit for relay 9WTFSA will be held open substantially continuously and this relay will release and open the circuits for relays 9ECTM and 9CD. Relay 9ETR will thereupon become steadily energized, and relay 9CD will release. Relay 9ETFSA will pick up, following the release of relay 9WTFSA, during a code interval when relay 9WTR is released, and then relay 9WCTM will pick up over back contact 195 and front contact 196 to hold relay 9WTR released and to supply steady current to the rails of section 7RT.

In Fig. 1, relay 7ETR will be picked up by the current supplied by relay 9WCTM during an interval between the code impulses supplied by relay 7ECTM so that relay 7ETFSA will pick up and open its back contact 60. This will hold relay 7ECTM released, enabling relays 7ETR and 7ETFSA to become steadily energized.

When the westbound train above referred to vacates the block, the code operation of relay 6RTCTM and of relay 7WTR is resumed. Relay 7WTFSA picks up in response to the first code impulse received by relay 7WTR but since relay 7ETFSA is also energized, relays 7CD and 7HR remain released, and relay 7WS is released by the opening of the back contact 13 of relay 7WTFSA. Relay 7WCTM then becomes steadily energized over the circuit including back contacts 63, 62, 61 and front contact 60, to supply steady current to section 6RT. The apparatus is now in its normal condition as shown in the drawings.

It will be seen from the foregoing that the control limits for the signal in approach to signal 9W extend to point E and have not been shortened by the removal of the westbound signal from point E to point F, and that the control limits for signal 9W include section E-F, due to the control of the signal relay 9HDR by the code detector relay 9CD for that section.

The operation of the system when set up for eastbound traffic movements will now be described. These operations are generally similar to those already described except for those operations which involve train movements through section E-F.

In the normal inactive condition for eastbound train movements, the eastbound traffic control relay 8EFSR is energized and the westbound traffic control relay 8WFSR is released, and the cascade connected relays which are energized are the relays 6RTCTM, 7WTR, 7WTFSA, 7ECTM, 7WTR, 9WTFSA, 9ECTM, 10LTR and 10LTCTM.

When the signal control relay 6RHSR is energized by the operator to set the system into operation and to clear the signals for eastbound traffic, the circuit for relay 6RTCTM is opened and the energized relays release in cascade, and relay 10LTCTM upon releasing connects relay 10LTCTM to terminal 180B or 15B of a suitable source of

5 coded current, depending upon whether or not signal 10R has been cleared, and relay 10LTCTM is caused to supply 75 or 180 code to the rails of section 10LT. In response to this code relay 9ETR energizes relays 9WTFSA and 9CD, and supplies coded impulses over its back contact to relay 9WCTM which repeats them into section 7RT.

In Fig. 1, relay 7ETR is set into operation to 10 energize relays 7ETFSA, 7CD and 7HR, and if 180 code is being received, to also energize relay 7DR. Relay 7HR energizes the directional stick relay 7ES, and relay 7ES sets the code transmitters 75CT and 180CT into operation. Relay 15 7ETPR is now energized by relay 7ETFSA, and relay 7WCTM is supplied with 180 coded current over the circuit including back contact 63 and front contacts 62 and 112, a front contact of relay 7ETPR and back contact 73, and supplies 180 code to section 6RT.

The response of relay 6RTR to this code causes signal 6RA to display a proceed indication as explained in the Van Horn patent.

It will now be assumed that an eastbound train 20 governed by signal 6RA passes through the block. When the train enters the switch section 5T, the track relay 5TR releases and picks up the directional stick relay 6RSR over a contact closed by signal 6RA in its energized position. Relay 6RSR is held energized over a stick circuit following the return of the signal to stop until the train vacates sections 5T and 6RT and coded current is received over the rails of section 6RT. When the train enters section 6RT and shunts the track 25 relay 6RTR, relay 6RTFSA will release, disconnecting terminal B from line wire 23 so that relay 7WTPR will release to complete the lighting circuit for signal 7E, energizing lamp G or Y to cause the signal to indicate proceed or caution 30 depending upon whether relay 7DR is energized or not.

When this eastbound train enters section 7RT, the track relay 7ETR is shunted, releasing relays 7ETFSA, 7CD and 7HR, and also releasing relay 7DR if energized, so that lamp R of signal 7E 35 becomes lighted in place of lamp G or Y.

The release of relay 7ETFSA releases relay 7ETPR which opens the circuit for relay 7WCTM and stops the delivery of coded current to the 40 rails of section 6RT. The closing of back contact 60 of relay 7ETFSA completes the stick circuit for relay 7ES to maintain that relay picked up, but relay 7TPC now releases, since as shown by the drawing, this relay is controllable by relays AETP and 45 7ETFSA when relay 7ES is picked up.

The release of relay 7TPC reverses the 50 connections of the track battery for supplying current to the rails of section 7RT at its left-hand end and at the same time completes a circuit for relay 7ECTM which includes front contact 69 of relay 7ES, back contacts of relays AETP and 55 7TPC, contact 67 of the code transmitter 180CT and back contact 60 of relay 7ETFSA.

Relay 7ECTM now supplies 180 coded current 60 of reverse polarity to the rails of section 7RT at its entrance end. When the eastbound train passes from section 7RT into section 10LT, relay 9ETR is shunted and relay 9WCTM is held de-energized. Relays 9ETFSA and 9ETPR release, lighting lamp R of the opposing signal 9W.

When the eastbound train vacates section 7RT, relay AWTR responds in place of relay 9WTR, and the 180 code now being supplied to section 7RT is not repeated into section 10LT nor is this coded current effective to control signal 9W, due 75

to the fact that it is of reverse polarity. Relay AWTR energizes the slow release repeating relay AWTP which connects terminal B to line wire 24, thereby energizing relay 7ETPR to complete a circuit for relay 7WCTM over back contacts 63 and 62, front contact 61, a contact of the code transmitter 75CT, a front contact of relay 7ETPR and extending to terminal B at back contact 73.

Relay 7WCTM therefore supplies 75 code to section 6RT enabling signal 6RA to display a caution indication when section 7RT is vacated, provided the operator has reenergized its control relay as explained in the Van Horn patent. It will be seen that in this case the unoccupied condition of section 6RT is detected by the 75 code supplied to that section, and the unoccupied condition of section 7RT is detected by the coded current of reverse polarity supplied at point E and received over the track rails at point F, by the track relay AWTR.

The directional stick relay 6RSR releases when coded current is received over the rails of section 6RT, and if the operator has not reenergized the control relay for signal 6RA, the apparatus at that location will have assumed its inactive condition and relay 6RTCTM will now be energized to supply steady current to the rails of section 6RT as explained in the Van Horn patent. Relay 7WTR will be picked up by the current supplied by relay 6RTCTM during an interval between the code impulses supplied by relay 7WCTM so that relay 7WTFSA will pick up and open its back contact 73. This will hold relay 7WCTM released, enabling relays 7WTR and 7WTFSA to become steadily energized. Relay 7WTPR will be picked up by relay 6RTFSA or relay 7WTFSA to open the lighting circuit for signal 7E.

When the eastbound train vacates the block, 75 code is supplied to section 10LT and relay 9ETR resumes its code operation. Relays 9ETFSA and 9CD pick up, and relay 9ETPR is energized to open the lighting circuit for signal 9W. Since relays 9WTR and 9WTFSA are now released, relay 9WCTM is set into operation to repeat the 75 code received from section 10LT with a reversal of phase, into section 7RT, which section is also being supplied with 180 code of reverse polarity by relay 7ECTM. The current supplied by relay 9WCTM will be effective, during the intervals when relay 7ECTM is released, to energize relay AETR in place of relay 7ETR, due to the reversal of the connections to these relays, relay 7TPC now being in its released position. Relay AETR will therefore pick up, at least momentarily, and will energize its slow release repeating relay AETP, which in turn, energizes relay 7TPC thereby opening the circuit for relay 7ECTM to prevent further transmission of 180 code impulses of reverse polarity, and in addition, rendering relay 7ETR responsive to the 75 code impulses supplied by relay 9WCTM in place of relay AETR. Relay 7ETR therefore picks up relay 7ETFSA which maintains relay 7TPC picked up, and relay AETP releases, along with relays AWTR and AWTP of Fig. 2.

If the operator has already reenergized the control relay for signal 6RA so as to maintain the system in operation, relay 7WCTM at this time will be supplying 75 code to section 6RT and relays 7WTR and 7WTFSA will be released. In this case, when relay 7ETR resumes its 75 code operation relays 7CD and 7HR will pick up and relay 7ETPR will be held energized by relay 7ETFSA, and relay 7WCTM will supply 180 code

to section 6RT due to the closing of that branch of its circuit which includes front contact 62 of relay 7HR and contact 112 of the code transmitter 180CT.

- 5 If the apparatus at the location of signal 6RA has been restored to its normal inactive condition so that steady current is being supplied to section 6RT, relay 7WTFSA will be in its energized position, preventing the energization of 10 relays 7CD and 7HR when relay 7ETFSA picks up. In this case relay 7ES will be released by the opening of back contact 60, and will complete a circuit for relay 7ECTM over back contacts 69, 68 and 76 and front contact 73 so that relay 15 7ECTM will supply steady current to section 7RT. In Fig. 2 this steady current will over-ride the code and effect the reversal of the cut section apparatus in the manner already described for the opposite direction of traffic movement, 20 to cause steady current to be supplied to section 10LT and thereby energize relays 10LTR and 10LTFSA to stop the code operation of relay 10LTCTM. The apparatus will then be in its inactive condition for the east bound traffic direction, corresponding to the inactive condition for the westbound direction shown.

It will be seen from the foregoing that when the eastbound direction is set up, the control limits for the signal in approach to signal 7E 30 extend to point F to reach the location of the opposing signal 7W, but without shortening the control limits for signal 7E.

Although I have herein shown and described only one form of apparatus embodying my invention, it is understood that various changes and modifications may be made therein within the scope of the appended claims without departing from the spirit and scope of my invention.

40 Having thus described my invention, what I claim is:

1. In a signaling system for a stretch of single track railroad comprising a first and a second end section and an intermediate section, said sections being equipped with cascade connected coded track circuits arranged to be supplied with coded currents of a first or a second character at either end of the stretch, said coded track circuits controlling a first and a second intermediate signal for governing train movements in opposite directions through the intermediate section and also controlling approach signals at the ends of the stretch for governing train movements into the stretch, each signal being adapted to indicate proceed or caution depending upon whether the coded current which controls it is of said first or second character, the combination of decoding means and of directional relays for two directions controlled by the track circuits for the first end section and the intermediate section, means controlled by said directional relays effective when a given traffic direction is set up for rendering the decoding means responsive to the coded currents supplied over the rails of the second end section and intermediate section in cascade and for enabling said decoding means to energize the first intermediate signal in accordance with the character of said coded current and to also supply coded current of said first character to the rails of the first end section to enable its approach signal to display a proceed aspect, means for supplying train detecting current of a third distinctive character to the rails of said intermediate section only, whenever a train governed by the first intermediate

11

signal passes through such section, a track relay selectively responsive to the current of said third distinctive character received over the rails of the intermediate section when vacated by said train, means controlled by said track relay when energized for supplying coded current of said second character to the rails of said first end section to cause the approach signal at the end of such section to display its caution aspect, means for terminating the supply of current of said third distinctive character when coded current is again received over the rails of said second end section, means controlled by said directional relays effective when the opposite traffic direction is set up for energizing said decoding means if coded current is being supplied over the rails of said first end section, and for causing said decoding means to supply coded current of said first or second character, depending upon whether or not it is energized, to the rails of the intermediate section and second end section in cascade for the control of the approach signal at the remote end of said second end section, and line circuit means rendered effective when said current supplied by said decoding means is received at the opposite end of said intermediate section for energizing the second intermediate signal to cause such signal to display its caution or proceed aspect dependent upon the condition of said decoding means.

2. In combination with a stretch of railway track comprising a first and a second end section and an intermediate section equipped with cascade connected coded track circuits, and having an intermediate signal for governing traffic movements into the intermediate section from said first end section and an approach signal for governing traffic movements in the same direction into said first end section, means for supplying coded currents of a first or second frequency to the rails of the second end section at one end of the stretch for the control of said intermediate signal and for the control of said approach signal, decoding means at the intermediate signal location adapted to cause the intermediate signal to display a caution or proceed aspect when coded current of said first or second frequency is received over the rails of the cascade connected intermediate and second end sections and to also supply coded current of the second frequency to the rails of the first section to cause the approach signal to display its proceed aspect, means for supplying train detecting current of a distinctive character to the rails of the intermediate section only, whenever a train governed by said intermediate signal passes through such section, means selectively responsive to the current of said distinctive character received over the rails of the intermediate section when vacated by the train for supplying coded current of the first frequency to the rails of the said first end section to cause the approach signal to display its caution aspect, and means for terminating the supply of current of said distinctive character as soon as the train vacates the second end section and coded current is again received over the rails of such section and is supplied at the adjoining end to the rails of the intermediate section.

3. In combination with a stretch of railway track comprising a first and a second end section and an intermediate section equipped with cascade connected coded track circuits, and having an intermediate signal for governing traffic movements into the intermediate section from

12

said second end section and an approach signal for governing traffic movements in the same direction into said second section, means for supplying coded currents of a first or second frequency to the rails of the first end section at one end of the stretch for the control of said intermediate signal and for the control of said approach signal, decoding means at the junction of said first end section and intermediate section adapted to supply coded current of the second frequency to the rails of the cascade connected intermediate and second end sections to cause the approach signal to display its proceed aspect when coded current of said first or second frequency is received over the rails of said first end section, code detecting means at the intermediate signal location selectively responsive to coded current received over the rails of said intermediate section, a signal relay for controlling said intermediate signal, a circuit for controlling said signal relay which is closed only when said code detecting means is energized to cause the intermediate signal to display a caution or proceed aspect depending upon whether said decoding means is responding to coded current of said first or second frequency, means for detecting when said signal relay circuit is closed comprising a series connected relay in said circuit at the location of said decoding means, and means controlled by said series connected relay for preventing the decoding means from supplying coded current of the second frequency to the rails except when the circuit for said signal relay is energized.

4. In a reversible track circuit system for an intermediate section in a stretch of railway track, said section having a transmitter relay at each end which is supplied at times with impulses of coded current in accordance with traffic conditions in an adjoining section in said stretch, and having a source of current and a first biased polar track relay at each end connected in series to the track rails over contacts of the associated transmitter relay in such manner that when such relay is supplied with coded current its contacts periodically disconnect the adjacent source from the track rails without disconnecting the track relay, each such track relay being responsive to current of the polarity normally supplied at the opposite end but not to current of the polarity normally supplied to the rails at the adjacent end of said section, the combination of the foregoing with normally inactive pole changer contacts in the circuit connecting the track relay and source to the rails at one end of the section, a second biased polar track relay at each end of said section which is connected to the track rails over a contact of the associated transmitter relay closed only when the adjacent source is disconnected, each second track relay being responsive only to current of reverse polarity supplied thereto by the source at the opposite end when said pole changer contacts are reversed, means controlled by the first track relay at said one end for reversing said pole changer contacts when a train enters said section at said one end, and for concurrently supplying coded current to the associated transmitter relay, whereby such relay is caused to connect the source of current at said one end periodically to the rails to supply impulses of reverse polarity thereto when said pole changer contacts are reversed, means for restoring said pole changer contacts to normal in response to the energization of the second track relay at said one end when current of

reverse polarity is supplied thereto over the rails of said section, signaling means controlled by each first track relay for indicating the unoccupied condition of said section when such relay is supplied with impulses of normal polarity over the rails of said section, train detecting means for indicating when such section is vacated by a train, and means for energizing said train detecting means in response to the energization of the second track relay at the opposite end of the stretch when current of reverse polarity is supplied thereto from the source at the location of said pole changer contacts.

5. In a reversible track circuit system for an intermediate section in a stretch of railway track, said section having a transmitter relay at each end which is supplied at times with impulses of coded current, and having a source of current and a first biased polar track relay at each end connected in series to the track rails over contacts of the associated transmitter relay in such manner that when such relay is supplied with coded current its contacts periodically disconnect the adjacent source from the track rails without disconnecting the track relay, each such track relay being responsive to current of the polarity normally supplied at the opposite end but not to current of the polarity normally supplied to the rails at the adjacent end of said section, means governed by each first track relay for supplying impulses of coded current to the rails of an adjoining section in said stretch, such adjoining section having means for operating the transmitter relay associated with such track relay to supply impulses of coded current to the rails of said intermediate section, the combination of the foregoing with normally inactive pole

changer contacts in the circuit connecting the track relay and source to the rails at a first end of said intermediate section, a second biased polar track relay at each end of such section which is connected to the track rails over a contact of the associated transmitter relay closed only when the adjacent source is disconnected, each second track relay being responsive only to current of reverse polarity supplied thereto from the opposite end when said pole changer contacts are reversed, means controlled by the first track relay at said first end of the intermediate section for causing said pole changer contacts to assume their reverse position when a train enters said intermediate section from an adjoining section at said first end, means for periodically operating the transmitter relay associated with said first track relay to supply coded current of reverse polarity to the rails at the first end of the section, effective whenever said pole changer contacts are reversed, means for restoring said pole changer contacts to normal in response to the energization of the second track relay at said first end when current of reverse polarity is supplied thereto over the rails of said intermediate section, train detecting means for indicating when said intermediate section is vacated by a train, and means for operating said train detecting means in response to the energization of the second track relay at the second end of such section when current of reverse polarity is supplied thereto from the source at the location of said pole changer contacts.
